[57] CLAIM

The ornamental design for a sports undergarment, as shown and described.

DESCRIPTION

FIG. 1 is a perspective view of a sports undergarment showing my new design; the broken lines shown in FIGS. 1, 2, and 5 being understood to represent stitching;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof, the left side being a mirror image.
